INVENTOR -

Albert Abbe Griswold

by Chas. H. Luther

ATTORNEY:

UNITED STATES PATENT OFFICE

ALBERT ABBE GRISWOLD, OF PROVIDENCE, RHODE ISLAND

ROLL-ROOFING FASTENER

Application filed October 21, 1926. Serial No. 143,266.

My invention has reference to an improvement in the means for securing the lower edge portion of roll roofing, to the roofs of buildings.

5 Roll roofing has heretofore been secured to roofs, sidings and the like, by laying it lengthwise of the roof, the lower edge of an upper course overlapping the upper edge of the next lower course of roll roofing. The roll roofing 10 is then secured to the roof or siding by driving nails through it into the roof or siding. The nail holes thus formed in the roll roofing will cause it, sooner or later, to leak, thereby ruining the utility of the roll roofing and the 15 greater portion of all roll roofing leaks are caused by nail holes through the roofing material.

The object of my invention is to improve the means for securing roll roofing or the like 20 to roofs, thereby eliminating the driving of nails or the like, through the overlapping edge portion of the roll roofing.

A further object of my invention is to provide roll roofing with roll roofing fasteners, 25 each fastener having a loop shaped fastening member which is made a part of the roll roofing.

Another object of my invention is to simplify the construction of roll roofing fasteners, whereby the cost of such fasteners is reduced to a minimum.

30 My invention consists in the peculiar and novel construction of means for fastening roll roofing to roofs and the like, said fastening means having details of construction, as will be more fully set forth hereinafter and claimed.

Figure 1 is a top view of a portion of a roof 35 looking in the direction of the arrow α in Figure 3 and showing the upper edge portion of a strip of roll roofing nailed to the roof and the lower edge portion of a strip of roll roofing in position to be secured in place, by my improved roll roofing fasteners.

40 Figure 2 is a lower edge view, partly in section, of a piece of roll roofing showing on the roll roofing and forming an integral part thereof, the fastening loops of the fastening members.

45 Figure 3 is a transverse sectional view

through the roof and roll roofing, taken on line 3, 3, of Figure 1 and looking in the direction of the arrow β , with the next upper course of roll roofing in position to be laid and secured in place.

55 Figure 4 is a sectional view similar to Figure 3 showing the next course of roll roofing laid and secured in place, and

Figure 5 is a perspective view of the main body or under fastening member of a fastener and showing the same in the shape or open position that it is supplied to the trade for use.

60 In the drawing 6, 6, indicates the roof boards of a roof, 7, 7, roll roofing and 8 my improved roll roofing fastener which consists of an attachable under fastening member 9 and a loop shaped fastening member 10, permanently secured to the roll roofing adjacent the edge of the roll roofing. The roof boards 6, 6, may also represent the sheathing on the outer walls of a building.

65 The roll roofing 7, 7, is usually laid in strips lengthwise of the roof, first a narrow strip at the roof edge and then the strips are laid full width, the lower edge portion of each upper course overlapping the upper edge portion of the next lower course, as shown in Figure 4.

70 The attachable under fastening member 9 is formed preferably of sheet metal and is 75 constructed to have a flat elongated base arm 11, in which is an aperture 12, said base arm 11 terminating into a reduced and rounded end 13. The base arm 11 has a bent over end portion 14 which merges into an overlapping upper arm 15 having a downwardly bent clamping finger 16 in a position to enter and pass through the aperture 12. This clamping finger 16 has a pointed projection 16a at

80 its bent portion, as shown in Figures 3 and 5. The upper arm 15 also has a narrowed end portion 17, with a hook shaped end portion 18 which is turned back over the narrowed end portion 17 and terminates into a bent back end 19, which normally contacts with the narrowed end portion 17, thereby forming a thin opening between the end portion 17 and the hook shaped end 18, for securing the hook shaped end portion 18 to a loop shaped fastening member 10.

The loop shaped fastening member 10 may be made of any suitable material such as tape, cord or wire. When made of wire the loop fastening portion 20 lays parallel with the under surface of the roll roofing 7, the ends 5 21, 21, of the loop are then forced into the roll roofing 7 and then bent over, thereby securing the loop fastening members 10, 10, to the roll roofing 7, as shown in Figure 2. The top coating or finishing coat of asphalt 10 is then applied to the roll roofing thereby covering and water-proofing the loops.

When my improved roll roofing fasteners are put to use, the operation of fastening the 15 lower edge portion of a strip of roll roofing in place on a roof, is as follows. The upper edge portion of a lower course of roll roofing is nailed to the roof boards 6, 6, by nails 22, 22, a predetermined distance apart, or practically the distance apart of the loop shaped 20 fastening members 10, 10, on the roll roofing. The hooked shaped end portion 18 of the under fastening member 9 is then forced through a looped shaped fastening member 10, in the direction of the arrow *c*, in Figure 25 3, and the rounded end 13 of the under fastening member 9 inserted under the upper edge of the lower course of roll roofing, as shown in Figure 3. This is continued the 30 entire length of the strip of roll roofing, one under fastening member 9 to each upper loop fastening member 10 and the under fastening members 9, 9 lying between the nails 22, 22, as shown in Figure 1. The upper strip 35 of roll roofing is now brought downwards over the lower course of roll roofing, thereby forcing the base arms 11, 11, of the under fastening members 9, 9, under the upper edge portion of the previously laid and nailed 40 course of roll roofing. Pressure is now applied to the upper course of roll roofing over the fastening members, thereby forcing the base and upper arms of the under fastening member 9, together. This forcing the arms 45 of the under fastening member together forces the end portion of the clamping finger 16 through the aperture 12 and then, striking the roof boards 6, 6, it is bent under the base arm 11, thereby locking the two arms of 50 the under fastening member together, thus preventing the lower edge portion of the roll roofing from lifting up. This operation also forces the pointed projections 16a, 16a, into the roof boards 6, 6, as shown in Figure 4, 55 thereby preventing an upward movement of the roll roofing. The bent back end 19 of the hook shaped end 18 of the underfastening member 9 prevents a retrograde movement of the loop 10 in the hooked shaped end portion 18 of the under fastening member 9 and locks the upper loop shaped fastening member 10 to the under fastening member 9.

Having thus described my invention I claim as new:

65 1. A roll roofing fastener comprising an

upper and an under fastening member, the upper fastening member being in the form of a loop and forming an integral part of the roll roofing and the under fastening member having an element which fastens to the 70 upper fastening member, an element adapted to go under the edge portion of roll roofing previously laid, an element adapted to lock the two previously mentioned elements together and a pointed element adapted to penetrate the roof boards of a roof, for the purpose as described.

2. The combination with flexible roll, roofing material in the form of a long wide strip of a series of loops extending lengthwise of the strip adjacent one edge thereof, each loop being secured at its ends to the underside of and forming an integral part of the strip, for the purpose as described.

In testimony whereof, I have signed my 85 name to this specification.

ALBERT ABBE GRISWOLD.
